UNITED STATES PATENT OFFICE.

WILLIAM A. LORENZ, OF HARTFORD, CONNECTICUT.

DESIGN FOR A CAN OR JAR.

SPECIFICATION forming part of Design No. 35,070, dated September 10, 1901.

Application filed August 12, 1901. Serial No. 71,847. Term of patent 14 years.

To all whom it may concern:

Be it known that I, WILLIAM A. LORENZ, a citizen of the United States, residing in Hartford, in the county of Hartford and State of Connecticut, have invented a new and original Design for Cans or Jars, of which the following is a specification.

My design relates to the external contour of cans, jars, and similar receptacles.

o In the drawings, in which similar numerals designate corresponding parts, Figure 1 is a top view, and Fig. 2 a side view, of a can or jar embodying my design.

The jar is approximately cylindrical, and comprises the body 10, surmounted by a top portion of a diameter smaller than that of the body and consisting of the comparatively narrow annular zone 11 and the annular band

12, separated by the peripheral groove 13, which is approximately semicircular in cross- 20 sectional outline. The body 10 of the jar is provided near its upper and lower ends with the peripheral fluted bands 14, separated by the interval 15.

Having described my invention, what I 25 claim as new, and desire to secure by Letters Patent, is—

The design for a can or jar substantially as shown and described.

In testimony whereof I have signed my 30 name to this specification in the presence of two subscribing witnesses.

WILLIAM A. LORENZ.
